UNITED STATES PATENT OFFICE.

ASHLEY C. BENNETT, OF MINNEAPOLIS, MINNESOTA.

CARBURETER.

1,133,527.

Specification of Letters Patent. Patented Mar. 30, 1915.

Application filed March 12, 1913. Serial No. 753,754.

To all whom it may concern:

Be it known that I, ASHLEY C. BENNETT, a citizen of the United States, and a resident of Minneapolis, in the county of Hennepin and State of Minnesota, have made certain new and useful Improvements in Carbureters, of which the following is a specification.

My invention relates to carbureters for internal combustion engines and my special object is to provide a carbureter that will operate with gasoline or kerosene or fuels of a like nature in one and the same carbureter by means of the proper application of the waste heat of the exhaust gases of the engine to the fuel before mixing with air in the mixing chamber. When used with gasoline and the like no heat is applied and the carbureter operates in the usual manner. When, however, it is desired to use kerosene and the like, heat is applied to assist in the production of a gaseous fluid from the fuel.

In order to enable those familiar with the art to which my improvement relates to more fully understand the operation and merits thereof, a particular embodiment of my improvement is shown in the accompanying drawing and referred to in the following specification, like characters of reference indicating similar parts throughout the drawing.

In the drawing, Figure 1 represents a partly sectional view of my carbureter showing also a manner of attaching to the exhaust manifold of the engine. Fig. 2, represents a partly sectional view taken on the line A—B, in Fig. 1, and showing the form of the inner end of the primary air passage and its relation to the stand pipe or column shown in the center of Fig. 1.

The fuel fluid is admitted to the bowl 1, by the valve 2 and is maintained at a constant level as shown approximately at the line C—D by the usual float 3 and arm 4 operating said valve 2. Air vents 5, 5 are provided around the upper part of said valve 2 to maintain atmospheric pressure within the bowl 1 at all times. Above the bowl 1 is the mixing chamber 6 connecting with the suction chamber 20 and the suction pipe of the engine by means of a suitable connection 7, and with the atmosphere by means of the primary air passage 8 and the

secondary air passage 9 and the valve 10. 55 The air valve 10 is held to open at the proper pressure by means of the spring 25.

In the center of the mixing chamber 6 is an upright stand pipe 11 in which is a plurality of small jet holes 12—12 through which the fuel is drawn by suction into the mixing chamber 6. This stand pipe is fully described and covered by my former United States Patent Number 927,211, issued July 6th, 1909, and is here shown in an improved 65 form. A needle valve 13 controls the flow of fuel from the bowl 1 through the passage 14 and into the stand pipe 11. A three-way valve 15 is interposed in the fuel supply pipe by means of which either gasoline 70 or kerosene may be admitted to the supply valve 2 as desired. In the construction shown the gasoline supply would be connected to the elbow 16 and the kerosene supply to the opposite elbow 17. A second pipe 75 18 similar to stand pipe 11 but shown in a horizontal position for convenience and provided with a nozzle or jet openings 19, 19, is inserted through in the suction chamber 20 and connects by means of an elbow 21 80 and an automatic check valve 22 with the water supply. Additional control is provided with the water supply by means of the needle valve 23 within the stand pipe. A throttle valve 24 within the suction chamber 20 serves to regulate the flow of the mixture to the engine in the usual manner. The usual drain cock 26 is provided in the bottom of the bowl 1.

Entering at the top of the mixing chamber 6 and passing down through the stand pipe 11 and the bowl 1 is a passage 27 for the exhaust gases which connects at its upper end with the exhaust manifold 28 of the engine. A jacket 29 covers the bowl 1 and 90 the space left between said jacket and bowl is connected with the exhaust passage 27 by means of a return bend 30. The final exhaust is made at the exhaust opening 31 in the opposite side of the jacket 29. A wing 100 valve 32 serves to control the admission of the exhaust gases to the passage 27. The inner end of the primary air passage 8 is divided to partly encircle the lower part of the stand pipe 11 as shown in Fig. 2. 105

When operated with gasoline and the like the water supply valve 23 is closed as may be the exhaust controlling valve 32.

In operating the gasoline control valve 13 is opened the desired distance and the engine rotated by hand or other means. The suction thus created in the suction chamber 20 and mixing chamber 6 draws air in through the primary air passage 8 over the gasoline contained in the lower part of the mixing chamber 6 and also draws gasoline up into the stand pipe 11 in proportion to the suction created by the motor and out through the jet openings or nozzle into the mixing chamber 6. The gasoline is thus evaporated or vaporized and mixed with the air drawn in through the primary air passage 8 and the resultant mixture is drawn by suction into the engine cylinders.

When running at low speeds the primary air passage 8 supplies all air needed to form a proper mixture for combustion. When running at high speeds, however, the suction is greater than at low speeds and the gasoline is raised to a greater height in the stand pipe 11 and as more of the jet openings 12, are thus brought into use a greater amount of fuel is delivered to the air and thereby to the cylinders. The secondary air valve 10 is so regulated and held by the spring 25 that it will now open and supply the extra amount of air needed to assist in burning the large amount of fuel delivered to the engine; the throttle valve 24 serving to regulate the speed of the engine in the usual manner.

When the engine is running on gasoline and it is desired to change to kerosene, the three-way valve 15 in the supply pipe is turned to admit kerosene to the supply valve 2. The exhaust controlling valve 32 is then turned to admit the exhaust or a part thereof to pass through the passage 27 through the center of the stand pipe 11 and the bowl 1 and around the outside of the bowl 1 to the final exhaust 31 which may be connected to a muffler if desired. As the walls of the passage 27 are very thin where it passes through the stand pipe 11 the heat of the exhaust gases soon heats these walls to a high temperature and the exhaust passing down through and around the bowl 1 also raises the temperature of the bowl and the contained fluids to a point below the distilling point of said fluids.

The heated gasoline contained in the bowl being rapidly used by the engine is replaced by kerosene. The heated kerosene being drawn up into the stand pipe and around the heated walls of the passage 27 becomes gaseous and being drawn out into the mixing chamber 6 through the jet openings 12, is mixed with air and drawn into the engine cylinders. The air is not heated before mixing and serves to cool the heated fuel before entering the cylinders.

On high speeds a greater amount of fuel is drawn into the stand pipe 11 and a corre-

spondingly greater amount of heat is delivered by the exhaust gases to aid carburation.

It is evident that on heavy load speeds a greater amount of fuel is burned and the temperature of the engine cylinders will rise and pre-ignition may result to the fuel, therefore other means of cooling besides by the cool air in the mixture is provided.

The second multiple jet 18 is connected to the water supply by means of the valve 22 which closes automatically when the engine is not in operation and serves to shut off the water supply.

In operation the valve 22 is raised by the suction in the suction chamber and by the water pressure and water is admitted by the regulating needle to the multiple jet 18 and being drawn out through the jet openings 19 into the suction chamber 20 is mixed with the fuel and drawn into the engine cylinders. It must be remembered however that the prime object of my invention is to heat the fuel liquids before coming in contact with the air entering the mixture, and this air being at the mean temperature of the surrounding atmosphere serves to cool the heated fuel and thus enables the engine to be run with a less amount of water in the water jet than when the air is also heated.

It is evident that any part or all of the exhaust gases may be employed to heat the fuel and also that the exhaust gases may be passed through the exhaust passage 27 in either direction. The preferable construction is deemed to be that shown in which the hottest gases come in contact with the vaporizer first and then through and around the bowl when partially cooled.

It is obvious that various modifications in the construction and design of my carburetor may be made without departing from the spirit of my invention.

What I claim and desire to secure by Letters Patent of the United States is the following:

1. A carburetor comprising a relatively vertical pipe in communication with the exhaust pipe of the engine, a feed pipe surrounding said vertical pipe and having a series of apertures along one side thereof, a casing forming an air passageway about said last named pipe, and means for delivering oil into the space between the feed pipe and the vertical pipe.

2. A carburetor comprising a relatively vertical pipe in communication with the exhaust pipe of the engine, a feed pipe surrounding said vertical pipe and having a series of apertures along one side thereof, a casing forming an air passageway about said last named pipe, a fuel container below said casing and surrounding a portion of the vertical pipe, and means for admitting fuel oil from said container to the bot-

tom of the space between the feed pipe and the vertical pipe.

3. A carbureter comprising a relatively vertical pipe in communication with the exhaust pipe of the engine, a feed pipe surrounding said vertical pipe and having a series of apertures along one side thereof, a casing forming an air passageway about said last named pipe, means for admitting 10 air into said passageway from the side away from said apertures to be drawn through the passageway by the operation of the engine, and means for delivering oil into the space between the feed pipe and the vertical 15 pipe.

4. A carbureter comprising a relatively vertical pipe in communication with the exhaust pipe of the engine, a feed pipe surrounding said vertical pipe and having a 20 series of apertures along one side thereof, a casing forming an air passageway about said last named pipe, separate passageways for primary and secondary air for admitting said air into said first named passageway

from the side away from said apertures to 25 be drawn through the passageway by the operation of the engine, and means for delivering oil into the space between the feed pipe and the vertical pipe.

5. A carbureter comprising a relatively 30 vertical pipe in communication with the exhaust pipe of the engine, a feed pipe surrounding said vertical pipe and having a 35 series of apertures along one side thereof, a casing forming an air passageway about said last named pipe, a fuel container below said casing and surrounding a portion of the vertical pipe, means for conducting the exhaust gases from said vertical pipe against the outside of the walls of the fuel container, and means for admitting fuel oil 40 from said container to the bottom of the space between the feed pipe and the vertical pipe.
